UNITED STATES PATENT OFFICE

WOLFGANG HOFFMANN, OF NEW YORK, N. Y., ASSIGNOR TO LUMINATOR INC., OF CHICAGO, ILLINOIS, A CORPORATION OF ILLINOIS

DESIGN FOR A LAMP

Application filed October 19, 1931. Serial No. 41,436. Term of patent 14 years.

To all whom it may concern:

Be it known that I, WOLFGANG HOFFMANN, a citizen of the United States, residing at New York, in the county of New York and State of New York, have invented a new, original, and ornamental Design for a Lamp, of which the following is a specification, reference being had to the accompanying drawing, forming part thereof.

Figure 1 is a side elevation of the lamp, and Figure 2 is a sectional view taken on the line 2—2 of Figure 1.

I claim:

The ornamental design for a lamp, as shown.

In testimony whereof I affix my signature.
WOLFGANG HOFFMANN.
